US00D599776S

(12) **United States Design Patent**
Nakagawa

(10) **Patent No.:** US D599,776 S
(45) **Date of Patent:** ** Sep. 8, 2009

(54) **RADIO COMMUNICATION DEVICE**

(75) Inventor: **Masashi Nakagawa**, Osaka (JP)

(73) Assignee: **Icom Incorporated**, Osaka (JP)

(**) Term: **14 Years**

(21) Appl. No.: **29/274,627**

(22) Filed: **May 10, 2007**

(30) **Foreign Application Priority Data**

Nov. 30, 2006 (JP) 2006-032973

(51) **LOC (9) Cl.** **14-03**

(52) **U.S. Cl.** **D14/188**; D14/137

(58) **Field of Classification Search** D14/137,

D14/155, 168, 169, 188, 192–198, 204, 217,

D14/257, 258, 265, 496; 455/344–351; 369/6–12

See application file for complete search history.

(57) **CLAIM**

The ornamental design for a radio communication device, as shown and described.

DESCRIPTION

FIG. 1 is a top view of a radio communication device, embodying my new design;

FIG. 2 is a back view thereof;

FIG. 3 is a bottom view thereof;

FIG. 4 is a front view thereof;

FIG. 5 is a left side view thereof;

FIG. 6 is a perspective view thereof; and,

FIG. 7 is a right side view thereof.

Portions of the radio communication device shown in broken lines form no part of the claimed design.
